UNITED STATES PATENT OFFICE.

JOHN NATER, OF WEST HOBOKEN, NEW JERSEY.

MANUFACTURE OF EMBROIDERY.

1,315,148.

Specification of Letters Patent. Patented Sept. 2, 1919.

Application filed September 13, 1918. Serial No. 254,007.

To all whom it may concern:

Be it known that I, JOHN NATER, a citizen of the United States, and a resident of West Hoboken, in the county of Hudson and State 5 of New Jersey, have invented new and useful Improvements in the Manufacture of Embroidery, of which the following is a full, clear, and exact description.

The invention relates to the manufacture 10 of embroidery by the etching or so-called Plauen process, in which the design is stitched with cotton, linen, metallic or other non-silk threads on a web of silk, and then the latter is destroyed by an acid bath thus 15 leaving the embroidery intact. Embroidery produced by this process has its threads, especially those forming the groundwork and the picots, severely deranged or pulled out of shape so that the original design appears more or less distorted, as shown in 20 Figure 6.

The object of the present invention is to provide certain new and useful improvements in the manufacture of embroidery according to the etching process whereby the embroidery including its minutest detail is maintained in its original shape (see Fig. 25 5), and an exceedingly fine finish is given to the embroidery without requiring pressing or ironing or rehandling of the goods, thus reducing the cost of production to a minimum.

In order to produce the desired result a piece of embroidery as received from the 35 embroidery machine is wound on a skeleton or open frame to form a package in which the embroidery is arranged in superimposed layers, and then the package is subjected to an acid bath capable of destroying the silk 40 web carrying the embroidery, and then the embroidery is unwound from the frame and is then in marketable condition without requiring pressing, ironing or other further treatment.

45 In order to carry this method into effect, use is made of special means shown in the accompanying drawings, in which similar characters of reference indicate corresponding parts in all the views.

50 Fig. 1 is a perspective view of the skeleton or open frame;

Fig. 2 is a plan view of the embroidery produced on the silk web and as received from the embroidery machine, the ends of the silk web being provided with covering 55 pieces of muslin or similar non-silk textile fabrics;

Fig. 3 is a cross section of the frame with the web of silk and the embroidery thereon wound upon the frame in superimposed 60 layers;

Fig. 4 is a reduced end view of the same and showing the threads for holding the piece of silk in stretched position on the frame;

Fig. 5 is a plan view of a piece of embroidery produced according to my improved process; and

Fig. 6 is a similar view of a similar piece of embroidery produced under the now prevailing process.

The embroidery 10 is produced by the usual embroidery machine on a web of silk 11, the embroidery shown in Fig. 2 being in the form of narrow bands connected with 75 each other at intervals at adjacent edges by suitable stitches to form a piece of embroidery usually a yard wide and ten yards long. In practice, three such pieces are sewed together end by end to form a piece 80 of thirty yards in length, and this piece is provided at the ends with end pieces 12 and 13 of muslin or other non-silk textile material, sewed or otherwise fastened to the ends of the piece. The silk web 11 with its embroidery 10 and the end pieces 12 and 13 is now wound up tightly on an open or a skeleton frame 15, preferably formed of wire netting 14 stretched around spaced transverse bars 16, 17 and corner pieces 18, 90 19 spaced from the main pieces 16 and 17, the several pieces 16, 17, 18 and 19 being preferably made of wood. The circumference of this frame is preferably a yard and when the piece of silk is wound upon this 95 frame it forms approximately thirty superimposed layers with the end piece 12 covering the wire netting 14 and the end piece 13 inclosing the outermost layer of the silk web and its embroidery. While winding up the 100 web of silk 11 on the frame 15, the web is held stretched in a transverse direction dur-

ing the winding-up process so that the embroidery remains in the original state in which it was produced on the web of silk 11. In practice, the frame 15 is slightly wider 5 than the web of silk 11, and after the latter has been wound up on the frame, then the sides of the web of silk 11 and those of the end pieces 12 and 13 are fastened by stitches 20 to the sides of the frame 15 at the netting 10 14, thus holding the wound-up web of silk and its end pieces 12 and 13 in the transversely stretched position.

It will be noticed that on winding up the web of silk 11 with the embroidery 10, and 15 the end pieces 12 and 13, on the frame 15, a package is formed which can be readily handled and this package is now submerged in an acid bath, preferably containing potassium or other chemicals capable of destroying 20 the web of silk 11 without affecting the embroidery 10. After the web of silk is destroyed the package is removed from the bath and, if desired, is next subjected to a bleaching bath and is then washed and dried 25 in the usual manner. After this has been done, the threads 20 are cut or removed and then the piece 13 and the embroidery 10 are unwound from the frame 15, after which the end pieces 12 and 13 are detached from the 30 embroidery.

It will be noticed that during the treatment described the embroidery is held in wound up and stretched condition on the frame 15, and hence the embroidery threads 35 are not liable to be deranged or pulled out of shape so that the original design as produced on the embroidery machine is maintained to its minutest details. On account of the embroidery being wound up tightly and being liable to slightly shrink during the washing and drying operations, the layers of embroidery are firmly superimposed even after the web of silk is destroyed and hence when the embroidery is unwound it is found to be 40 45 in perfectly flat condition, requiring neither pressing nor ironing, that is, the embroidery after being unwound is ready for the market.

Having thus described my invention, I 50 claim as new and desire to secure by Letters Patent:-

1. The herein described process of manufacturing embroidery, which consists in producing the embroidery with cotton or metallic threads on a web of textile material other than cotton or metal, then winding up the web with the embroidery thereon to form a package in which the web with its embroidery is arranged in superimposed layers, then subjecting the package to an acid bath to destroy the web, and finally unwinding the embroidery. 55 60

2. The herein described process of manu-

facturing embroidery which consists in producing the embroidery on a web of silk with 65 non-silk threads, then winding up the web of silk and its embroidery to form a package and holding the web of silk stretched in a transverse direction during the winding up operation, then subjecting the package to an 70 acid bath to destroy the web of silk and leave the embroidery intact, then washing and drying the package, and finally unwinding the embroidery.

3. The herein described process of manufacturing embroidery which consists in producing the embroidery on a piece of silk, then winding the web of silk with the embroidery thereon onto a skeleton frame and holding the said web of silk stretched in a 80 transverse direction during the winding up operation thereby forming a package in which the web of silk is arranged in superimposed layers, then subjecting the package to an acid bath to destroy the web of silk, then 85 washing and drying the package and finally unwinding the embroidery from the frame.

4. The herein described process for manufacturing embroidery of cotton or metallic threads, which consists in producing the embroidery on a web of silk, then winding up the web of silk with the embroidery thereon and holding the web of silk in a stretched condition both transversely and longitudinally during the winding up operation to 95 form a package in which the web of silk and its embroidery are held tightly wound up, then subjecting the package to the action of an acid bath to destroy the web of silk, then washing and drying the package and 100 finally unwinding the embroidery.

5. The herein described process for manufacturing embroidery of cotton or metallic threads, which consists in producing the embroidery on a web of silk, then attaching 105 protecting sheets of cotton to the ends of the web of silk, then winding up the web of silk with the embroidery and end pieces on a skeleton frame and holding the web of silk stretched in a transverse direction to 110 form a package in which the web of silk and embroidery are held in superimposed layers with one end piece covering the frame and the other end piece forming a covering 115 for the package, then fastening the sides of the web of silk and end pieces to the frame, then subjecting the package to the action of an acid bath to destroy the web of silk, then washing, bleaching and drying the package, and finally unwinding the embroidery. 120

6. In the herein described process for manufacturing embroidery according to the etching process, the step of winding up the web of silk with the embroidery thereon on a skeleton or other frame and holding the web 125 of silk tightly stretched in a transverse di-

rection during the winding up operation and subjecting the wound up embroidery to the action of a decomposing agent to destroy the web of silk.

5 7. In the herein described process for manufacturing embroidery according to the etching process and as set forth in claim 6, the

step of attaching the sides of the web of silk to the frame to hold the web of silk in stretched position during the subsequent destruction of the web of silk by the said decomposing agent as set forth in claim 6. 10

JOHN NATER.
